AIR GUIDE DEVICE

Martin M. Gracer, Levittown, N.Y.
(71 Laurel Drive, Massapequa Park, N.Y.)

Filed Oct. 10, 1957, Ser. No. 689,425

8 Claims. (Cl. 138—39)

This invention relates to duct constructions of heating, ventilating and air conditioning systems and more particularly to a duct construction having particular utility in providing efficient air passage through elbows and turns found in duct systems.

This application is a continuation-in-part of my application Serial No. 363,640, filed June 23, 1953, entitled Air Guide Device, now Patent No. 2,861,597.

Still more particularly, this invention relates to a novel air turning device and to a novel blade or vane supporting plate or rail therefor.

It is well known in the art to provide in branches, particularly at sharp corners or bends of a duct assembly, a series of vanes or blades of a curvature to guide air or the like efficiently around such corners or bends. In the early development of these devices, they were factory made and frequently comprised a pair of spaced parallel upper and lower support plates or rails connected by a series of spaced blades, the ends of which were welded or brazed, or fastened by expensive means to both the said supporting rails.

While the above structure possessed the desired rigidity, the wide variety of duct sizes and angular bends which were required resulted in development by me of turning vane units which could be cut to size and assembled on the job, and which were adaptable to be used in a wide variety of air turning situations which the installing worker may encounter.

While I have provided air turning assemblies and sub-assemblies having the requisite adaptability, the structural rigidity and aerodynamic efficiency of such assemblies have, in general, been found to lack some of the features of assembled units which are brazed or soldered together. Particularly, such assemblies have, under conditions of unworkmanlike assembly, developed whistles, rattles, noises and other like objectionable characteristics indicating, in addition, a loss in air turning efficiency as well as an inadequate rigidity.

Accordingly, it is an object of my invention to provide an efficient, easy to assemble air turning unit capable of being adapted to a wide variety of ducting situations and which, even in prolonged use, is free from objectionable noises, rattles, whistles and other defects.

A further object of my invention is to provide an improved blade or vane supporting plate or rail with the advantages aforesaid, and which is adapted to employ blades which may be made on the job of readily available sheeted metal stock. Still a further object of this invention is to provide a rail of the type and for the purposes described which is adaptable, without alteration, to be used in connection with blades of double wall construction.

Still another object of this invention is to provide a rail of the type described which acts as a guide for proper mounting of the blades and permits speedy and secure blade mounting to be accomplished through the use of simple tools. Still a further object of this invention is to provide a rail of the type described which includes

2

novel means for temporarily maintaining the blades or rails in predetermined mounted position prior to permanent fastening, thereby facilitating the fastening operation and also permitting trial and error testing of blade alignment, to determine optimum blade placement for the installation to be made.

To attain these objects and such further objects as may appear herein or be hereinafter pointed out, I make reference to the accompanying drawing forming a part hereof, in which—

Figure 1 is a perspective view of an assembled air turning device, parts being broken away to show details;

Figure 2 is a magnified plan view of the inner rail blade illustrating the position of a double wall blade;

Figure 3 is a magnified plan view of the outer portion of an air turning assembly;

Figure 4 is a section taken on the line 4—4 of Figure 3;

Figure 5 is a section taken on the line 5—5 of Figure 3 with the addition of a chisel in blade crimping position;

Figure 6 is a schematic diagram of a portion of a typical ducting system, illustrating the use of an air turning assembly;

Figure 7 is a fragmentary perspective view of my invention during a stage of assembly;

Figure 8 is a fragmentary section taken on the line 8—8 of Figure 7;

Figure 9 is a fragmentary perspective view of my invention during a stage of assembly;

Figure 10 is a magnified fragmentary section taken on the line 10—10 of Figure 9 with the addition of a chisel in blade crimping position.

Reference is now made to the drawings forming a part hereof wherein, in accordance with one form of this invention, a pair of blade rails 10—10 serves as the medium for supporting the blades B with their ends in butt-joint contact by the formation of a joint positioned to hold the blade in predetermined arcuate position.

The rail 10 is a strip of sheet metal initially stamped or otherwise shaped to raise on the inner face repeats of spaced, identically projecting portions, identified generally as 11. The projecting portions 11 comprise specifically the raised, crescent-shaped lead portion 12, trailing portion 13, and the inner face portion 14. The raised, angular side portions 15, 15 deepen, gradually defining at points of maximum depth a pair of protuberances 16, 16. The walls 17, 17 surrounding the protuberances 16, 16 are graded or tapered so as to present a streamlined surface to streams of air flowing from any direction.

The walls 17, 17 adjacent the protuberances 16, 16 terminate in the parallel fold lines 18, 18, thereby defining on the face opposed to the raised faces, a pair of downwardly depending guide channels 19, 19 (see Figure 3).

Across each protuberance 16 is formed a guide slot 20, each such slot lying approximately normal to the fold lines 18, 18 and thus being angularly directed relative to the margins of the sheet 10. The slots 20 are preferably tapered to have a wide entrance or mouth portion 21 at the lowermost portion of the protuberance 16, tapering to a constricted throat or edge portion 22 adjacent the face of the rail 10. The slots 20 additionally include opposed, deformable tabs or lips 23 and 24 for purposes to be described. These tabs or lips may be serrations 23', 24' as shown in Figure 2.

Through the use of the vane rail above described, fabrication of an air turning assembly is a simple matter. Two identical lengths of rail 10, each sufficient to span the bend or elbow, are provided with shaped end cuts C, C', to match the angular or mitred configurations of the elbow, as is well known.

Blades B, which may optionally be formed of rectangles of sheeted metal, are cut to the length desired and are

arched or bowed or rolled to assume the correctly outlined curvature by manually pressing portions of the longitudinal blade edges into the angularly disposed slots 20. The blades B will be retained within the slots 20 through the wedging action of the lugs 23, 24 against the side walls of the blades, and by the tapered nature of the slots 20 to thereby also accommodate the slots to metal of different thickness.

With the blades thus positioned, the top rail 10 may be similarly mounted with its slots 20 encompassing the theretofore free edges of the blade B. The thus assembled structure will be frictionally retained in position with sufficient rigidity to permit experimental adjustment of blade extension to either side of the rail and the like by actual introduction into the elbow, prior to permanently joining the blades B to the rails 10.

With correct blade positioning thus assured, the air turning device may be permanently assembled, such assembly being accomplished by the crimping or turning over of the intersecting portions 25 of the blades B which extend through the slots 20 of the inwardly extending protuberances 16 and project from the outer faces of the rails 10 (see Figures 3, 5, 7, 8, 9, 10).

While the blades may be locked to the rail 10 by splitting the extending blade portion within the socket formed by the protuberance, as will be described in detail in connection with Figures 9 and 10, the rail assembly includes a novel guide structure to facilitate the crimping operation while assuring the intimate blade-rail contact necessary for efficient, noiseless operation.

With the portion 25 of the blade B extending through slot 20, a chisel T is inserted and directed along and within the guide channel 19, with the working edge 26 thereof against the extending portion 25 and a bevel 27p lying adjacent the guide 19 of the rail 10. When the thus positioned chisel is struck, the portion 25 is turned from the position shown in dotted lines to the position shown in solid lines (lower rail, see Figure 5) and at the same time, a downward angular component tending to seat and draw the blade B edge-tightly against the rail 10 is developed by the contact of the bevel 27p of the chisel T with the guide 19. The guide 19 likewise assures correct positioning of the chisel T against the projecting portion 25, thereby causing crimping and forming in the direction of optimum holding power against the wall 16b.

It will be readily recognized that the guides 19 may serve also to direct a peening hammer P against the projections 25, to secure a tight fit between the blades B and the rails (see Figures 7 and 8). When the hammer P is swung approximately in the direction of the arrow (see Figure 7), the angularly disposed guide 19 will insure that the hammer strikes the portion 25 normal to the slot 20, thereby forming a vane-to-rail connection for optimum strength. As may be seen from Figure 8, the downwardly inclined nature of the guide 19 will permit the hammer to strike the portion 25 simultaneously with the guide 19, thereby tending to seat the blade more intimately against the rail as the portion 25 is turned from the upright position (Figure 8 in dotted lines) to the turned or locking position adjacent the wall 16b.

A further method of locking the blades B within the slots 20 is illustrated in Figures 9 and 10 where a chisel T is placed against the projecting portion 25 of the blade B, with the working edge 26 of the chisel arranged to lie substantially normal to the edge of the rail 10. When the thus positioned chisel is struck a sharp blow, the portion 25 will be divided into two tabs, 25b, 25p, which tabs will be folded by the bevels 27p of the chisel from the partially spread position (Figure 10, dotted lines) to the anchored position (solid lines), where they will lie entirely within the protuberances 16, with one or the other of the tabs 25p, 25b adjacent the wall 16b.

It has been determined that imperfections in the butt-joint vane blade junction, such as slight spaces between the said parts or burried lateral blade edges, can cause in-

efficiencies in air turning characteristics as well as annoying noise manifestations, such as whistling, rattling and the like. I have provided my device with raised ridge portions 12 and 14 (see Figure 4) surrounding and contoured to the rail-vane junctions, the said ridge portions in large measure acting to minimize or eliminate noises and inefficiencies in operation caused by undue exposure or gaps of the said junctions to direct air flow.

While my device has primary utility in connection with 10 blades or vanes of the single wall type, it will be understood that all the advantages aforesaid also pertain when a double wall blade B' is employed. In the latter case, the shielding and noise minimizing action as aforesaid is provided for the rear wall of the double blade by the 15 ridges 12 and 13.

In Figure 6 I have illustrated a portion of a typical ducting system including air turning devices variously disposed to perform several air turning applications. The tapered wall construction of the protuberances 16 assures 20 minimum resistance to air flow and more efficient air turning deflection, and consequent increases in efficiency over other known air turning devices, as well as serving to rigidify the rails against vibration under the influence of air flow.

25 Likewise, great economies are effected by the simplicity of construction and assembly of my device, without any corresponding sacrifice of quality; the above advantages being retained in a unit suitable for use in a wide variety of air turning applications.

30 Having thus described my invention and illustrated its use, what I claim as new and desire to secure by Letters Patent is—

1. A rail adapted to be joined by crimping to air turning blade members to form an air guide, comprising 35 sheeted metal shaped to provide on one face a plurality of spaced-apart, inwardly extending protuberances, said protuberances having opposed walls defining slots having extended edges defining tabs spaced from the edges of said slots, thereby to provide a temporary frictional anchorage for said blade members prior to crimping, said protuberances defining on the other face depending guide channels directed substantially normally to said slots whereby a tool may be readily aligned and guided into blade crimping position against a portion of said blades projecting through said slots.

45 2. A rail in accordance with claim 1 wherein said extended edges are serrated.

3. A rail in accordance with claim 2 wherein the walls defining said slots are tapered to constricted throat portions adjacent said rails, said edges and throat portions 50 forming a two point suspension for frictionally anchoring said blades within said slots prior to crimping.

4. A device in accordance with claim 1 wherein said guide channel is inwardly directed at an angle, having a downward angular component along said rail calculated 55 to divide the thrust of a chisel struck when resting against a projecting portion of a blade and said guide channel into components comprising a blade crimping component and a blade seating component, said last named component operating to draw said blade tightly against said rail as said first component crimps said blade.

5. In a rail adapted to maintain a plurality of arcuate air guide blades in butt-joint contacting relations to said rail to form junctions with said rail, junction shield means arranged to extend along the line of said junction and out 65 of the plane of said rail on the junction side thereof, thereby to minimize aerodynamic noises and air flow disturbances.

6. A rail in accordance with claim 4 wherein said shield means comprise arcuate deflecting ridges.

7. A rail in accordance with claim 5 wherein said ridges define shielded recessed portions in which said blades may be arranged to lie in butt-joint contacting junction.

75 8. An air turning assembly comprising a plurality of

arcuate blades suspended between parallel upper and lower sheeted metal rails and forming butt-joint junctions with each of said rails, said rails including ridge means arranged to be proximately spaced from said junctions and to follow generally said arcuate contours, thereby shielding said junctions from direct aerodynamic flow and minimizing aerodynamic disturbances, such as whistling.
